UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CLOTH BOARD FOR LOOMS.

Application filed August 22, 1927. Serial No. 214,506.

This invention relates to improvements in cloth boards for looms and it is the general object of the invention to provide a cloth board which shall assist in keeping 5 the shed lines well defined for the passage of shuttles, especially in the weaving of multi-ply fabrics.

In such fabrics as woven heavy belting, the warp threads are separated by parallel 10 planes of weft threads but the fabric is usually woven with a single shuttle so that weft can be laid in but one plane at a time. When weft is being laid in the top plane, for instance, most of the warp threads will 15 be down and there will be a tendency to overbalance the lifting force of the comparatively few warp threads in the upper shed, the effect of which is to move the fell of the cloth below its normal or mid position. On the other hand when the shuttle 20 is laying the lowest pick of filling the major part of the warp threads will be up and the effect will be to raise the fell above its normal or mid position. This causes variation 25 in the vertical position of the fell of the cloth which produces a corresponding change in the shed lines and the space through which the shuttle may pass. The shuttles in looms of the type to which the 30 invention more closely relates must travel in fixed paths and the variation in the shed is objectionable for this reason. It is an important object of my present invention to provide a support for multi-ply fabrics 35 to be located closely adjacent the fell and so placed as to sustain the fabric in a relatively high position so that when the lowest pick of filling is being laid and the majority of the warp threads are lifted the fabric 40 being woven will still rest on the support.

It frequently happens that a loom which at one time is weaving multi-ply fabric may later be used to weave simpler cloth and it is desirable to be able to remove the support 45 for the cloth and allow the latter to have contact with the breast beam at a relatively forward point in the travel of the cloth. It is accordingly a further object of my invention to provide a removable cloth board or 50 support and it is a still further object of the invention to render said support adjustable as regards its location with respect to the fell of the cloth.

I make that part of the device which is 55 permanently secured to the breast beam with

a curved surface and so proportion the other part which has direct contact with the fell of the cloth as to require the fabric to move to the curved surface in a slightly downward direction, the purpose of this construction 60 being to keep the fabric against the cloth board when the warps are in their highest position.

With these and other objects in view which will appear as the description proceeds, my invention resides in the combination and arrangement of parts hereinafter described and set forth in the claims.

In the accompanying drawings, wherein I have shown a convenient embodiment of 70 my invention,

Fig. 1 is a vertical section through a portion of a loom having my invention applied thereto and showing the cloth support in relatively rear position where it will support a multi-ply fabric.

Fig. 2 is a detailed top plan view taken in the direction of arrow 2, Fig. 1,

Fig. 3 is an enlarged top plan view of certain parts shown in Fig. 2 and taken in 80 the direction of arrow 3, Fig. 1,

Fig. 4 is a vertical section on line 4-4 of Fig. 3, and

Fig. 5 is a transverse vertical section on line 5-5 of Fig. 4.

While my invention is applicable to various types of looms I have chosen to illustrate the same in connection with a narrow ware loom such as may be employed in the weaving of heavy belting. A loom frame 90 10 supports a warp beam 11 and there is provided the usual lay or batten 12 in which move the narrow ware shuttles one of which is indicated at 13 in Fig. 1. A suitably driven take-up roll 14 provides means 95 for advancing the fabric through the loom and the cloth may be collected on cloth roll 15. The harness frames 16 may be operated by any of the well-known harness motions such as a dobby and the loom is provided with a breast beam 17 formed as an I-beam. The parts described heretofore may of common construction and form no part of my present invention, the harness frames moving in a predetermined order to 100 raise the warp threads to provide a shed 105 for the passage of the shuttle 14.

In carrying my invention into effect I provide a series of cloth boards or supports, one for each shuttle and read space, but as 110

these supports are all the same I have illustrated but one of them in the drawings. Referring particularly to Figs. 2, 3, 4 and 5 it will be seen that I have provided a stand 30 having ears 31 through which extend bolts 32 to secure the frame or stand to the web of the breast beam. As shown more particularly in Fig. 4 the stand is provided with an upwardly and rearwardly curving surface 33 which terminates in a substantially horizontal portion 34. The curved portion is connected to the ears 31 by means of vertical walls 35. The stand 30 is secured permanently to the breast beam and may be used when a comparatively simple fabric is being woven to guide the same through a slot 36 cut in the beam to permit the passage of the cloth, said slot being shown more particularly in Figs. 3 and 4.

When it is desired to weave a heavy or multi-ply fabric a cloth support 40 may be employed, said support having a forwardly extending shank 41 with side walls which fit closely into grooves 42 formed in the underside of the stand 30. A securing bolt or screw 43 passes through the shank and into the rear portion of the stand, said bolt extending through a slot 44 in the shank 41 of the support extending in the general direction in which the cloth travels. The rear member or portion of the support is provided with an upwardly facing shoe 45 which is in a plane slightly above that occupied by the horizontal surface 34 of the support. By loosening the bolt 43 and moving the support the shoe 45 may be altered with respect to the fell of the cloth to control the sheds as the harnesses operate.

From the foregoing it will be seen that I have provided a simple cloth board to support a relatively heavy fabric, said support having one member which is permanently secured to the loom frame and provided with a curved surface and said support having another member secured to the first part and extending rearwardly toward the fell of the goods and having an upper cloth supporting surface which is somewhat above the highest point of the curved surface on the first member. It will further be seen that relative adjustment between the two parts of the support may be made and that if desired the rear support may be entirely removed.

Having thus described my invention it will be apparent that changes and modifications may be made therein by those skilled in the art without departing from the spirit and scope of the invention and I do not wish to be limited to the details herein disclosed, but what I claim is:

1. In a loom having a breast beam, a two-part cloth support one part of which is se-

cured directly to the breast beam and has a cloth engaging upwardly and rearwardly curved surface, the other part of the support having a cloth engaging portion, and a forward extension rigid with the cloth engaging portion and projecting under the curved surface and secured to the first part. 70

2. In a loom having a breast beam, a two-part cloth support one part of which is secured directly to the breast beam and has a cloth engaging upwardly and rearwardly curved surface, the other part of the support having a cloth engaging portion, a forward extension rigid with the cloth engaging portion and projecting under the curved surface and secured to the first part, and co-operating means formed on the two parts defining a sliding connection between said parts whereby the second named part may be moved relatively to the first named part 80 in the direction in which the cloth moves on the loom. 85

3. In a loom having a breast beam, a primary support secured to the breast beam and having an upwardly and rearwardly 90 cloth engaging surface, a guideway formed on the under side of the primary support extending in the general direction in which the cloth moves through the loom, and a secondary cloth support having a cloth engaging upwardly facing surface and a forward extension to be received by the guideway, said forward extension projecting under the curved surface and secured to the primary cloth support. 95

4. In a loom having a breast beam, a primary cloth support secured to the breast beam and having an upwardly and rearwardly curved cloth engaging surface, a guideway formed in the primary cloth support extending substantially parallel to the path along which the cloth moves in the loom, said guideway lying under the curved surface, a secondary cloth support having an upwardly facing surface to engage the under side of the cloth, a forward extension formed as part of said secondary support which is received by the guideway of the primary support, said extension having a slot therein substantially parallel to the guideway in the primary support, and means passing through the slot and engaging the extension and secured to the primary support to hold the secondary support securely in position relatively to the primary support. 110 115

5. In a loom having a breast beam, a primary cloth support secured to the breast beam and having an upwardly and rearwardly curved cloth engaging surface, a guideway formed in the primary cloth support extending substantially parallel to the path along which the cloth moves in the loom, said guideway lying under the curved surface, a secondary cloth support having 125 130

an upwardly facing surface to engage the under side of the cloth, a forward extension formed as part of said secondary support which is received by the guideway of the primary support, said extension having 5 a slot therein substantially parallel to the guideway in the primary support, and means passing through the slot and engaging the extension and secured to the primary support to hold the secondary support securely 10 in position relatively to the primary support, said extension lying under the curved surface of the primary support.

In testimony whereof I have hereunto affixed my signature.

ELBRIDGE R. HOLMES.
